UNITED STATES PATENT OFFICE

MALCOLM W. MCRAE, OF CHICAGO, ILLINOIS, ASSIGNOR TO CRANE CO., OF CHICAGO, ILLINOIS, A CORPORATION OF ILLINOIS

RADIATOR SHIELD

Application filed May 3, 1930. Serial No. 449,508.

This invention pertains to an improvement in a removable metallic radiator shield, more particularly to that type employing a sheet metal construction, in which the shield is fitted between the individually assembled sections of the radiator subsequently to the assembly of the radiator.

It is appreciated that the use of sheet metal shields for heating radiators has been previously resorted to, but, to my knowledge, there has not yet been produced a radiator shield which will be as easily and rigidly applied as that embodying the principles of my invention described herewith.

15 One of the principal purposes of this invention is to provide for a shield which can be conveniently and yet firmly fixed to the radiator sections when assembled, forming an integral radiator unit.

20 Still a further object is to produce a shield which is relatively cheap to manufacture, simple to remove when desired and at the same time unlikely to become accidentally dislodged during or after installation.

25 A shield constructed in accordance with my invention may be installed in the usual radiators and is particularly adapted to the type radiator which will be hereafter described. Other advantages will become apparent in considering the following description given in connection with the accompanying drawings in which:

Fig. 1 is a vertical transverse view between two adjoining sections of a radiator and 35 shield made in accordance with one embodiment of my invention.

Fig. 2 is a top view of three sections of a radiator, assembled with the shields between the sections, and

40 Fig. 3 is a side elevation of a portion of a radiator provided with shields embodying my invention.

Referring to the figures, the assembled radiator is composed of a number of sections 45 2, each of which is made of cast metal and formed to provide a number of communicating passages, through which the steam or other heating fluid passes to radiate heat through the shell or metal thickness of the 50 radiator. The sections 2 are joined by means

of the usual number of threaded nipples, not shown, contacting at the points 3 and 4 for the upper and lower communications, respectively. Each of the sections is preferably made with parallel spaced ribs 5, which form 55 grooves, therebetween as shown, to receive the radiator shield although a single rib as is usual in radiator construction will suffice.

The shield 7, formed of a strip of suitable sheet metal, and preferably of concave in 60 cross section, as indicated at 8, and of proper width to fit between and follow closely the guides formed between the ribs 5. The end portion of the strip is bent over to form a top section 9. The angle of bend is preferably 65 slightly less than a right angle before being installed. This is done so that when the shield is pressed into the assembled sections from the top it is necessarily sprung slightly, making it more rigid and tight.

It is unnecessary, therefore, to provide for any special form of shearing at the points 10 and 11 which are merely rounded, respectively at the upper and lower ends of the shield, thus facilitating production without 75 regard to a special fit or form for the purpose. Being concave in form, the surfaces 8 and 9 of the shield 7 afford a relatively easier surface to clean than those heretofore produced. At the same time this construction lends itself 80 readily to a convenient and effective installation, the rounded ends 10 and 11 aiding in the insertion of the shields between the radiator sections.

It is obvious that many changes may be 85 made in the details of construction without departing from the spirit and scope of this invention as defined in the claims appended hereto.

I claim:

1. A metallic radiator shield capable of being removably held between sections of a heating radiator, said shield consisting of a longitudinal relatively long strip having its outer face concaved throughout its length and having an end portion bent to form a lateral end portion of similar cross section, said shield being adapted to provide a relatively smooth surface between and continuous with 100

the outer surfaces of adjacent radiator sections.

2. A metallic radiator shield comprising a relatively long strip having its outer face concaved and having an end portion bent at 5 slightly less than a right angle to the remainder of the strip to form a short lateral end portion of similar concaved section, said concavity tending to produce compression between said shield and opposed sides of adjacent 10 radiator sections in both lateral and longitudinal positions, said shield also being adapted to provide a relatively smooth surface between and continuous with the adjacent outer surfaces of adjacent radiator sections.

In witness of the foregoing I affix my signature.

MALCOLM W. McRAE.
